ATTORNEY

This patent relates to oil well drilling apparatus, more particularly to slips used in rotary drilling tables, and to means for reducing the weight of such slips, and to a method of manufacturing the same and of mounting them on rotary drilling tables.

UNITED STATES PATENT OFFICE

2,010,938

LIGHT WEIGHT SLIP

Walter A. Abegg, Los Angeles, Calif., assignor of one-half to Baldwin Reinhold, Los Angeles, Calif.

Application May 14, 1934, Serial No. 725,467

10 Claims. (Cl. 24—263)

This invention relates to oil well drilling apparatus and particularly pertains to a slip for rotary drilling tables.

In the drilling of oil wells by the rotary methods the drill stem extends through a table, and is engaged by slips which hold the drill stem in fixed relation to the table. These slips are arcuate and represent segments of a circle concentric with the longitudinal axis of the drill stem whereby a set of slips may be arranged around the drill stem and positioned upon a seat in a rotary table, said seat being preferably tapered, the degree of taper agreeing with the taper formed on the outer face of the slips. When the drill stem is of a relatively small diameter the individual slips are of light weight and may be readily handled. However, as the diameter of the drill stem increases the size and weight of the slips increase and the larger sizes of slips of necessity are quite heavy, often each weighing 125 pounds. It will be recognized that in the course of a well drilling operation, and particularly when the well had reached a considerable depth, the manipulation of the slips would be a laborious task.

It is the principal object of the present invention therefor to provide slips of a design which will have maximum wearing qualities and a minimum weight whereby they may be readily moved from place to place and adjusted, and may be used for a considerable period of time without replacement, the structure further embodying means for permitting wearing surfaces to be renewed, and for preventing the slips from accidentally falling through the hole in the drill table. The present invention contemplates the provision of a slip for rotary well drilling operations which is designed to utilize a relatively small amount of metal suitably reinforced to provide a maximum strength and which also makes it possible to carry renewable wear plates.

The invention is illustrated by way of example in the accompanying drawings, in which:

Figure 1 is a view in elevation showing a rotary table upon which the slips of the present invention are used.

Fig. 2 is an enlarged view in central vertical section showing the construction of the slip with which the present invention is concerned, taken on irregular line 2—2 of Fig. 4.

Fig. 3 is a view in end elevation showing the slip.

Fig. 4 is a view in transverse section through the slip as seen on the line 4—4 of Fig. 2.

Fig. 5 is a view of the slip in transverse section as seen on the line 5—5 of Fig. 2.

Fig. 6 is a view in elevation showing the slip.

particularly illustrating the manner in which the wear plate is mounted and the reinforcement of the slip by which its light weight is obtained.

Referring more particularly to the drawings, 10 indicates a rotary table carrying a usual inner table 11. Extending through this table is a drill stem 12. Slips 13 are provided to fit within a tapered opening within the inner table 11 and to engage the drill stem 12. The slips as here shown are formed with an inner face 14 extending vertical and parallel to the outer face of the stem 12. This inner face is preferably formed with a plurality of longitudinally recessed grooves 15 which receive inserts 16, this portion of the structure being designed in accordance with the showing of Patent No. 1,834,316, issued to George E. McLagan, December 1, 1931, in which the lower end of each insert is secured at the bottom of the slip in a manner to have free rotation, and the upper end of each insert is secured by an insert lock plate 17, the details of which will be more fully described hereinafter. The body of the slip comprises the front arcuate face 18 on a radius the center of which is the longitudinal axis of the drill stem. This portion of the slip is relatively thin and reinforced by vertical ribs 19 and lateral ribs 20. The vertical ribs taper longitudinally and are arranged along the arc of a circle so that they may properly fit within the tapered seat occurring within the inner rotary table 11. For purposes of strength it is preferable that the group of ribs 19 are disposed in parallel relation to each other while terminating ribs 21 at the sides of each slip extend radially. The lower ends of the ribs 19 are tied together by a portion 22 which provides a downwardly and inwardly tapered shoulder 23. An arcuately extending web portion 24 ties the upper ends of the ribs together and is formed with an upwardly and inwardly tapered shoulder 25. The shoulders 23 and 25 extend arcuately and parallel. The length of vertical ribs 19 occurring between these shoulders is cut away to uniform depth. This provides a space to receive a wear plate 26. The wear plate 26 is arcuate in horizontal section and is formed with oppositely inclined faces at its ends. This plate can therefore be moved arcuately of the outer face of the slip and into position between the tapered shoulders 23 and 25 thereof, after which it is secured in position by screws 27 extending into the web 20. The terminating flanges 21 on each slip are of a length sufficiently less than the width of the plate so that the plate may be accommodated as it slides into position. The upper web 24 by which the vertical ribs are tied together is con-

caved and connects with the body portion 18' of the slip. At the upper end of the web 24 an outwardly projecting shoulder 28 occurs. This receives an overhanging flange 29 of the insert lock plate 17, which plate is of angle section and has a down turned flange 30 at its forward edge to stand in interlocking relation to an upward projection 31 of each of the inserts 16. Cap screws 32 may hold the lock plate 17 in position. It is preferable that the lock plate shall be formed with ears 33 which project outwardly and have openings 34 to receive the pintle pins of a handle 35. It may also be desirable to form the lock plate with projecting lugs 36. These lugs give an overall width 15 to each slip which is greater than the diameter of the hole in the rotary table through which the drill stem extends, and it is thus insured that the slips cannot accidentally fall through the opening in the table.

20 In operation of the present invention the slip is made according to a showing of the drawings and is preferably cast from light weight material, such for example as aluminum having extreme strength. After the inner face of the body member 18' has been machined to its proper arcuate configuration and the longitudinal recesses have been formed to provide seats for the inserts 16 the rear face of the ribs is machined to form the inclined faces 23 and 25 and to form a space for the wear plate 26. The wear plate 26 may then be slipped in position along an arcuate path as previously described and may be fastened by the screws 27. The inserts may be placed in their position within the recesses 15 and fastened by the lock plate 17. It will then be evident that the vulnerable points of wear on the front and back faces of the slip will be protected by inserts 16 and wear plates 26, both of which are made of steel having extreme wearing qualities.

40 By the use of light weight metals having considerable strength, such for example as certain aluminum alloys, and by protecting the wearing surfaces of the slips with hardened steel inserts and wear plates, it is possible to materially reduce the weight of the slips without sacrificing strength or wearing qualities, and in fact it has been found that an elimination of as much as sixty-five per cent of the normal weight of a drill slip may be obtained in this manner.

50 It will thus be seen that the device here disclosed may be built to be extremely light in weight without sacrificing strength, and at the same time will be provided with wear means adapted to be readily applied and renewed, thus furnishing all of the desired features of a drill slip without the weight which is now necessary in order to give the slip adequate strength.

While I have shown the preferred form of my invention, as now known to me, it will be understood that various changes may be made in the combination, construction, and arrangement of parts by those skilled in the art, without departing from the spirit of the invention as claimed.

65 Having thus described my invention, what I claim and desire to secure by Letters Patent is:

1. A drill slip comprising an arcuate face plate adapted to conform to the outer face of a drill stem to be gripped thereby, a plurality of longitudinally extending ribs formed integral with said face plate, the outer edges of said ribs being downwardly and inwardly tapered, said tapered faces being arcuately arranged with relation to the section of the slip whereby the arcuate face plate will conform to the face of the drill stem and

the inclined ribs will conform to a tapered seat of a rotary table, and an arcuate wear plate adapted to be disposed over the tapered faces of the ribs whereby a wear member will be interposed between the ribs and the tapered seat of the rotary drill table. 5

2. A drill slip comprising an arcuate face plate adapted to conform to the outer face of a drill stem to be gripped thereby, a plurality of longitudinally extending ribs formed integral with said face plate, the outer edges of said ribs being downwardly and inwardly tapered, said tapered faces being arcuately arranged with relation to the section of the slip whereby the arcuate face plate will conform to the face of the drill stem and the inclined ribs will conform to a tapered seat of a rotary table, an arcuate wear plate adapted to be disposed over the tapered faces of the ribs whereby a wear member will be interposed between the ribs and the tapered seat of the rotary drill table, and wear means mounted on the inner face of the slip and interposed between said face and the face of the drill stem. 20

3. A drill slip comprising an arcuate face plate adapted to conform to the outer face of a drill stem to be gripped thereby, a plurality of longitudinally extending ribs formed integral with said face plate, the outer edges of said ribs being downwardly and inwardly tapered, said tapered faces being arcuately arranged with relation to the section of the slip whereby the arcuate face plate will conform to the face of the drill stem and the inclined ribs will conform to a tapered seat of a rotary table, an arcuate wear plate adapted to be disposed over the tapered faces of the ribs whereby a wear member will be interposed between the ribs and the tapered seat of the rotary drill table, and wear means mounted on the inner face of the slip and interposed between said face and the face of the drill stem. 30

35 4. A drill slip comprising a body member having a front face which is curved horizontally and straight vertically, said face conforming to the surface contour of the drill pipe, a back face curved horizontally and tapered longitudinally to conform to a seat in a rotary drill table within which the slip is seated, and means formed as a part of the slip having an overall dimension greater than the maximum width of the hole in the rotary table whereby the slip will be prevented from falling through the hole. 50

5. A drill slip having a front face conforming to a segment of the face of a drill stem, and having a back face tapered to conform to a tapered seat in a rotary table, the back face being constructed with wear means adapted to be interposed between the tapered face of the slip and the tapered face of the seat in the rotary table, said wear means being in the form of an arcuate wear plate adapted to sheath the tapered face of the slip and to be removably secured thereto, said securing means including seats formed on the back surface of the drill slip and with which the wear plate interlocks at its upper and lower edges. 55

6. A drill slip characterized by its light weight which comprises an arcuate face plate adapted to conform to a segment of the circumference of a drill stem, the opposite edges of said plate being such as to permit a plurality of plates to be grouped around the drill stem, a plurality of 70

longitudinal and lateral ribs formed on the back of said plate reenforcing the edges and body thereof, a centrally disposed wear plate extending longitudinally of the center-most of said ribs and being positioned to be interposed between the ribs of the tapered seat of a rotary table.

7. A drill slip characterized as being of relatively light weight and comprising an arcuate plate adapted to conform to a segmental face of a drill stem, a plurality of longitudinally extending back ribs formed integral with the said arcuate plate and tapering downwardly and inwardly to conform substantially to the tapered seat of a rotary table, transverse back ribs connecting and reenforcing said longitudinally tapered ribs, under-cut seats formed in the face of upper and lower transverse rib sections, a longitudinally extending wear plate interlocked with said seats, and means for securing the same in position.

8. A drill slip comprising an arcuate body plate formed with a longitudinal recess in its forward face, an overhanging flange at the lower end of said recess, a wear member adapted to be positioned within said recess and having a lip interlocking with said overhanging flange at its lower end and an upwardly projecting lip at its upper end, a lock plate disposed at the upper end of the arcuate plate and having an overhanging flange engaging the upper lip of the wear member, cooperating means for interlocking the lock member with the arcuate plate, and fastening means therefor.

9. A drill slip comprising an arcuate body plate formed with a longitudinal recess in its forward face, an overhanging flange at the lower end of said recess, a wear member adapted to be positioned within said recess and having a lip interlocking with said overhanging flange at its lower end and an upwardly projecting lip at its upper end, a lock plate disposed at the upper end of the arcuate plate and having an overhanging flange engaging the upper lip of the wear member, cooperating means for interlocking the lock member with the arcuate plate, fastening means therefor, and a handle carried by a part of said lock plate.

10. A drill slip comprising an arcuate body plate formed with a longitudinal recess in its forward face, an overhanging flange at the lower end of said recess, a wear member adapted to be positioned within said recess and having a lip interlocking with said overhanging flange at its lower end and an upwardly projecting lip at its upper end, a lock plate disposed at the upper end of the arcuate plate and having an overhanging flange engaging the upper lip of the wear member, cooperating means for interlocking the lock member with the arcuate plate, fastening means therefor, and a handle carried by a part of said lock plate, said lock plate having oppositely extending end portions giving the lock plate an over-all dimension greater than the opening through the seat of a rotary table.
